CLAIM

The ornamental design for a medical device for thermal treatment of male genitalia, as shown.

DESCRIPTION

FIG. 1 is a perspective view of a medical device for thermal treatment of male genitalia according to our new design; FIG. 2 is a top plan view thereof;

FIG. 3 is a side elevational view thereof, the opposite side being a mirror image;

FIG. 4 is a front elevational view thereof;

FIG. 5 is a rear elevational view thereof; and,

FIG. 6 is a bottom plan view thereof.
